SUPERHETERODYNE RECEIVER COMPRISING AUTOMATIC FREQUENCY CONTROL

Folkert Albert de Groot, Eindhoven, Netherlands, assignor, by mesne assignments, to Hartford National Bank and Trust Company, Hartford, Conn., as trustee

Application April 12, 1946, Serial No. 661,522
In the Netherlands April 12, 1943

Section 1, Public Law 690, August 8, 1946
Patent expires April 12, 1963

3 Claims. (Cl. 179—171).

1

The invention relates to improvements in or modifications of the invention described and claimed in the specification of copending U. S. patent application Serial No. 661,523, filed April 12, 1946.

The said specification relates to a superheterodyne receiver whose intermediate frequency part comprises a sharp filter for the selection of the carrier wave in which a control voltage for automatic frequency-control is generated with the aid of a frequency discriminator of which the said sharp filter forms part and to which one or more control-rectifiers are connected, whilst the intermediate frequency carrier wave is kept within the frequency-range selected by the filter solely by controlling by means of the said control voltage the tuning of the sharp filter. The filter may comprise one or more resonant circuits with reduced damping in which the damping reduction is generally effected by means of a back-coupled discharge system or by means of a discharge system in which a negative resistance occurs between two electrodes. The term "selecting" is construed herein to include the accentuation of the carrier wave with respect to the sideband frequencies as well as the separation or suppression of the carrier wave.

A receiver of this kind permits, for instance, of eliminating the serious distortion which frequently occurs due to the fact that the carrier wave of the signal received is attenuated more intensely than the sidebands (selective fading). This is achieved by the use in the receiving channel of a sharp filter which accentuates the carrier wave with respect to the sidebands. The tuning of this filter is influenced in such a manner by automatic frequency-control that the intermediate frequency carrier wave is kept within the frequency-range selected by the filter. In order to enable variation of the tuning of the filter through a comparatively wide range, use is preferably made of a filter comprising one or more resonant circuits with regenerative feedback.

The object of the present invention is to provide an especially suitable form of construction of the receiver above described which ensures an improved performance.

According to the invention, the said frequency discriminator is constructed in such manner that the automatic frequency-control occurs solely or substantially solely as a function of the detuning of the filter with respect to the carrier wave.

The said frequency discriminator is usually constructed in such manner that the carrier

2

wave applied to the discriminator is converted into two voltages, which are applied respectively in phase and in antiphase to a couple of push-pull connected control rectifiers and which, if the tuning of the filter is correct, have a given phase displacement which will be referred to hereinafter as the normal phase displacement and which is usually 90°. Now, if the discriminator network in addition to the filter whose tuning is controlled comprises one or more uncontrolled resonant circuits, the phase displacement between the two said voltages may diverge from the normal phase displacement, the filter being nevertheless tuned correctly, or be equal to the normal phase displacement, the filter being tuned incorrectly, this being due to the phase displacement brought about by the uncontrolled circuits. It is obvious that due to this the operation of the frequency-control is disturbed. This disadvantage is, however, avoided if care is taken that the uncontrolled circuits bring about the same phase displacement of the two said voltages, or in other words if these circuits do not cause a relative phase displacement between the said two voltages.

Care is therefore taken that the uncontrolled intermediate frequency circuits of the network have such a quality for the frequency of the intermediate frequency carrier wave that they do not cause a relative phase displacement between the voltages applied to the control rectifiers in phase and in antiphase respectively. If this condition is satisfied, these circuits no longer influence the value of the control voltage so that the automatic frequency-control merely depends upon the detuning of the filter with respect to the carrier wave.

In order that the invention may be clearly understood and readily carried into effect, it will now be set out more fully with reference to the accompanying drawing, in which one embodiment is illustrated.

The single figure of the drawing represents the intermediate frequency portion of a receiver to which the invention is applied. An intermediate frequency amplifying tube 1 is coupled to the control grid circuit of a discharge tube 4 via a resonant circuit 2 tuned to the intermediate frequency and a filter 3 formed by a resonant circuit with regenerative feedback. The filter 3 is constituted by a condenser 5 and two coils 6 and 7 connected in series. The damping circuit 3 is controlled by connecting the latter in three-point connection to the discharge tube 4. As related in copending U. S. Application Serial No.

661,523, it is generally necessary for the circuit to have its damping reduced to a marked extent, and the discharge tube is preferably also negatively backcoupled in such manner that the circuit is not damped by the negative feedback per se. This measure ensures that in the case the damping of the filter is reduced to a large degree, self-oscillation cannot occur under certain conditions. In the present case the negative feedback is obtained by means of a resistance 8, not shunted so far as intermediate-frequency currents are concerned, included in the cathode circuit of the tube 4. The presence of this resistance does not damp circuit 3.

The anode circuit of the discharge tube 4 includes a circuit 9 tuned to the intermediate-frequency and coupled capacitatively via a condenser 10 to a diode-detector 11 whose audio-frequency output voltage is supplied to an audio-frequency amplifier (not shown).

In addition, the circuit 2 has connected to it a circuit 12 which is also tuned to the intermediate-frequency and which has connected to it two push-pull connected control rectifiers (diodes) 13 and 14. The centre of the circuit 12 and the centre of the output resistance 15 of the two diodes 13 and 14 are connected to a coupling coil 16 which is coupled inductively to the intermediate-frequency circuit 9. The circuits 7, 9 and 12 and the coupling coil 16 constitute a discriminator network which jointly with the control rectifiers 13 and 14 connected to it constitutes a device for generating a control voltage for automatic frequency-control, said control voltage being set up across the said output resistance 15.

The control voltage is supplied to the control-grid of a discharge tube 17 shown in the drawing as a triode, whose anode current is passed through a magnetising coil 18. The inductance 6 is provided with a core of high-frequency iron on which the magnetising coil 18 is fitted. Variation of the direct current passing through this coil permits of varying the inductance of the coil 6 and hence the tuning of the sharp circuit 3 within certain limits.

Owing to the presence of a sharp circuit 3 the sideband frequencies of the intermediate-frequency signal are strongly attenuated with respect to the carrier wave, so that the risk of an apparent over-modulation of the signal occurring in the event of selective fading, which would be accompanied by a strong non-linear distortion of the low-frequency signal, is avoided. The linear distortion brought about by the attenuation of the sideband frequencies is eliminated by a suitable choice of the frequency characteristic curve of the audio-frequency amplifier.

The desired operation, however, requires that the tuning frequency of the circuit 3 always corresponds within narrow limits with the frequency of the intermediate-frequency carrier wave. This conformity is ensured by the automatic frequency-control, since, in the event of a divergence occurring between the said frequencies a control voltage of proper polarity is generated across the resistance 15 and modifies the inductance of the coil 6, to such an extent that the tuning frequency of the circuit 3 is again substantially put into agreement with the carrier wave frequency.

In order to achieve such conformity, it is, however, necessary, as set out above, that the frequency-control should depend solely or substantially solely upon the detuning of the circuit 3

5 with respect to the carrier wave and should not depend at the same time upon the frequency difference between the carrier wave and the tuning of the uncontrolled intermediate-frequency circuits 9 and 12. According to the invention, the circuits 9 and 12 are constructed in such manner that their quality factor

$$(Q = \frac{\omega L}{r})$$

is identical or substantially identical for the frequency of the intermediate-frequency carrier wave. If indeed the two circuits are of equal quality, they cause no relative phase displacement between the voltages supplied to the control rectifiers in phase and in antiphase respectively and consequently the output resistance 15 has occurring across it a control voltage which depends solely upon the phase displacement caused by the detuning of the circuit 3 with respect to the carrier wave, since the phase displacements occurring by reason of the frequency difference between the carrier wave and the tuning of the circuits 9 and 12, are identical and hence do not contribute towards a relative phase displacement between the said voltages.

What I claim is:

1. An amplifier circuit arrangement, particularly for use in a receiver for receiving signal voltages of carrier and sideband frequencies, comprising an amplifier having an input circuit and an output circuit for translating a first signal voltage having frequency components corresponding to said carrier and said sideband frequencies, a filter circuit sharply tuned to a frequency corresponding to said carrier frequency and coupled to the input circuit of said amplifier to apply a signal voltage of frequency corresponding to said carrier and sideband frequencies to said amplifier, means to couple said filter circuit to said amplifier to derive and apply to the input circuit of said amplifier a second signal voltage of frequency corresponding to said carrier frequency to reduce the damping of said filter, a frequency discriminator circuit having a first resonant circuit coupled to the input circuit and a second resonant circuit coupled to the output circuit of said amplifier to produce a frequency control voltage, means responsive to said control voltage to tune said filter sharply to an intermediate frequency corresponding to said carrier frequency, said first and said second resonant circuits having quality factors such that said frequency control voltage varies substantially solely proportional to the difference in frequency between the frequency to which said filter is tuned and the frequency of said signal voltages, and means coupled to the output circuit of said amplifier to derive an output voltage comprising said first signal voltage and said second signal voltage and having carrier frequency components relative to sideband frequency components greater than the carrier frequency component of said first signal voltage.
2. An amplifier circuit arrangement, particularly for use in a receiver for receiving signal voltages of carrier and sideband frequencies, comprising an amplifier having an input circuit and an output circuit for translating a first signal voltage having frequency components corresponding to said carrier and said sideband frequencies, a filter circuit sharply tuned to a frequency corresponding to said carrier frequency and coupled to the input circuit of said amplifier to apply a signal voltage of frequency corre-

sponding to said carrier and sideband frequencies to said amplifier, means to couple said filter circuit to said amplifier to derive and apply to the input circuit of said amplifier a second signal voltage of frequency corresponding to said carrier frequency to reduce the damping of said filter, a frequency discriminator circuit having a first resonant circuit coupled to the input circuit and a second resonant circuit coupled to the output circuit of said amplifier to produce a frequency control voltage, means responsive to said control voltage to tune said filter sharply to an intermediate frequency corresponding to said carrier frequency, said first and said second resonant circuits having substantially equal quality factors whereby said frequency control voltage varies substantially solely proportional to the difference in frequency between the frequency to which said filter is tuned and the frequency of said signal voltages, and means coupled to the output circuit of said amplifier to derive an output voltage comprising said first signal voltage and said second signal voltage and having carrier frequency components relative to sideband frequency components greater than the carrier frequency component of said first signal voltage.

3. An amplifier circuit arrangement, particularly for use in a receiver for receiving signal voltages of carrier and sideband frequencies, comprising an amplifier having an input circuit and an output circuit for translating a first signal voltage having frequency components corresponding to said carrier and said sideband frequencies, a filter circuit sharply tuned to a frequency corresponding to said carrier frequency and coupled to the input circuit of said amplifier to apply a signal voltage of frequency corresponding to said carrier and sideband frequencies to

said amplifier, means to couple said filter circuit to said amplifier to derive and apply to the input circuit of said amplifier a second signal voltage of frequency corresponding to said carrier frequency to reduce the damping of said filter, a frequency discriminator circuit having a first resonant circuit coupled to the input circuit and a second resonant circuit coupled to the output circuit of said amplifier to produce a frequency control voltage, means responsive to said control voltage to tune said filter sharply to an intermediate frequency corresponding to said carrier frequency, said first and said second resonant circuits having quality factors producing substantially equal phase displacements of the voltages there across whereby said frequency control voltage varies only in proportion to the frequency difference between the frequency to which said filter is tuned and the carrier frequency of said received signal voltages, and means coupled to the output circuit of said amplifier to derive an output voltage comprising said first signal voltage and said second signal voltage and having carrier frequency components relative to sideband frequency components greater than the carrier frequency component of said first signal voltage.
